DESIGN FOR A THERMOMETER

Ralph C. Wappner, Springfield, Ohio, assignor
to The Ohio Thermometer Company, Spring-
field, Ohio, a corporation of Ohio

Application January 10, 1946, Serial No. 125,434

Term of patent 14 years

(Cl. D52—7)

To all whom it may concern:

Be it known that I, Ralph C. Wappner, a citizen of the United States, residing at Springfield, Clark county, Ohio, have invented a new, original, and ornamental Design for a Thermometer, of which the following is a specification, reference being had to the accompanying drawing, forming a part thereof, in which

Fig. 1 is a front view of a thermometer embodying my new design.

Fig. 2 is a side elevation thereof.

Fig. 3 is a top plan view thereof.

I claim:

The ornamental design for a thermometer, substantially as shown.

R. C. WAPPNER.
